UNITED STATES PATENT OFFICE.

JOHN C. SIBISKI, OF BALTIMORE, MARYLAND.

ADJUSTABLE SOCKET WRENCH.

Application filed November 2, 1921. Serial No. 512,326.

To all whom it may concern:

Be it known that I, JOHN C. SIBISKI, a citizen of the United States, residing at Baltimore, in the city of Baltimore and State of Maryland, have invented certain new and useful Improvements in Adjustable Socket Wrenches; and I do hereby declare the following to be a full, clear, and exact description of the invention, such as will enable others skilled in the art to which it appertains to make and use the same.

The invention relates to wrenches of the socket type and aims to provide a tool of this character in which the socket is adjustable and adapted to clamp nuts of different sizes and shapes within certain limits.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a central longitudinal section of a wrench embodying the invention.

Figure 2 is a side view thereof.

Figure 3 is a view of the wrench as seen from the upper end.

Figure 4 is a view of the wrench as seen from the lower end, and

Figure 5 is a plan view of the paddle for adjusting and operating the wrench.

Corresponding and like parts are referred to in the following description and designated in the several views of the drawings by like reference characters.

The tool comprises an elongated socket 5 of rectangular form in transverse section. The upper end of the socket 5 is reduced and of polygonal form as indicated at 7 to receive a suitable handle as indicated in Figure 5 for rotation of the wrench when in operation. Two sides of the socket are approximately parallel and the other two sides have their end portion oppositely inclined as indicated most clearly in Figure 1. The inclined sides of the socket have their lower portions reversely inclined whereby to effect an opening or a closing of the jaws as the latter move longitudinally. The upper portions of the inclined sides of the socket are

preferably cutaway to expose the upper ends of the jaws and the portions of the nut in engagement therewith.

Similar or like jaws 3 are mounted within the socket 5 and their gripping ends are offset and project beyond the socket and are depressed upon their inner sides so as to engage adjacent faces of a nut or like parts and prevent slipping. The gripping faces of the jaws are toothed or corrugated to insure positive engagement with the nut or other part to be turned and prevent possible slipping. The outer faces of the upper end portion of the jaws 3 are oppositely inclined to conform to the inclination of the upper portions of the inclined side walls of the socket. An expansible helical spring 6 is interposed between the jaws 3 and normally serves to press the same apart and hold their outer faces in contact with the lower reversely inclined portions of the socket. Longitudinal movement of the jaws 3 within the socket 5 effects an opening or a closing of the jaws according to the direction of movement. Outward movement of the jaws 3 effect a closing thereof and inward movement of the jaws causes the same to open or separate. Figure 1 shows the jaws 3 at the limit of their inward movement and open to a maximum extent.

A nut 1 is disposed within the upper end of the socket 5 and has opposed studs 4 which enter openings formed in the upper ends of the jaws 3 whereby the nuts and jaws move together. A screw 2 in cooperative relation with the nut 1 has its upper end reduced and passed through an opening formed in the upper end of the socket 5, the projecting end receiving a cap 8 which is secured thereto by means of a pin 9. The upper end of the socket 5 is confined between the cap 8 and the shoulder formed at the base of the reduced end of the screw 2 thereby forming in effect a swivel joint, whereby the screw 2 may rotate freely while it is held against longitudinal movement. The cap 8 or like parts is of polygonal form to receive a handle or operating part whereby the screw 2 may be rotated.

The handle disclosed in Figure 5 is provided with a middle and an end opening 10 to fit the polygonal end 7 of the socket 5 whereby the wrench may be rotated when in service. The handle is also provided with an opening 11 to receive the polygonal cap 8 applied to the projecting end of the screw 2.

whereby the latter may be rotated to effect longitudinal movement of the nut 1 and the jaws 3 in engagement therewith. Outward movement of the jaws 3 cause them to ride upon the opposed reversely inclined portions of the socket 5 with the result that said jaws are pressed together to grip a smaller size nut or like part to be turned. The wrench may be adjusted so as to grip the part to be turned and thereby prevent possible displacement. After the wrench has been adjusted to the work it is rotated by means of the operating handle or equivalent part applied to the polygonal end 7 of the socket.

Bolts 4^a which have enlarged heads and which are threaded into the studs 4, are employed to prevent the jaws 3 from becoming accidentally disconnected from the studs 4.

20 What is claimed is:—

1. A device of the class described including a hollow socket having side walls, the sides of the socket being open between said walls and the top wall of the socket, a screw journaled in said top wall, a head on said screw exteriorly of the socket and resting on the top wall, a nut within the socket, jaws within the socket in engagement with and for which said sides of the socket constitute guides, the jaws having openings

therethrough, and means to extend through said openings to establish connections with the nut, and said means including detachable fastenings for application through the spaces of the socket above said sides. 35

2. A device of the class described including a hollow socket having inclined side walls and a handle-head above said walls, the sides of the socket being open between the said inclined sides and said head, a screw 40 journaled in the top wall of the head, a wrench-head on said screw exteriorly of the socket and resting on said first mentioned head, a nut within the socket and extending into the first mentioned head, jaws within the socket in engagement with said inclined sides, means to urge separation of the jaws at their gripping ends, the jaws having openings therethrough, projections on the nut extending into said openings, and detachable fastenings applicable to said projections through the spaces of the socket 45 above the inclined sides. 50

In testimony whereof I affix my signature in presence of two witnesses.

JOHN C. SIBISKI.
